Thurston & Bates

UNITED STATES PATENT OFFICE.

ALDEN BUSH, OF COLUMBUS, OHIO, ASSIGNOR OF ONE-HALF TO CHARLES A. HAWLEY, OF COLUMBUS, OHIO.

DENTAL PLUGGER.

SPECIFICATION forming part of Letters Patent No. 732,044, dated June 30, 1903.

Application filed July 30, 1902. Serial No. 117,593. (No model.)

To all whom it may concern:

Be it known that I, ALDEN BUSH, a citizen of the United States, residing at Columbus, in the county of Franklin and State of Ohio, have invented a certain new and useful Improvement in Dental Pluggers, of which the following is a full, clear, and exact description, reference being had to the accompanying drawings.

10 The object of my invention is to do away with many of the difficulties which are present in dental pluggers now in use and to provide one which will meet all the demands of the operator.

15 I have used in the following description the terms "touch-stroke" and "stipple-stroke." In order that the description may be perfectly clear and that persons using my invention may understand what I mean when I use them, I will describe the same. By a "touch-stroke" I mean a stroke which is received by the filling when the plugger-point is permitted to continuously rest upon it and the hammer allowed to hit the pin. This operation

20 would of course convey a sort of tamping action to the filling. By the other expression, "stipple-stroke," I mean a stroke whereby the filling is battered upon its face, and this sort of stroke is obtained by holding the

25 plugger-point away from the filling and allowing the hammer to hit the plugger-pin, so as to drive the point against the surface of the filling.

According to my invention the operator may 30 by one arrangement of the instrument obtain a touch-stroke or a stipple-stroke, as desired. By another arrangement he may obtain a stipple-blow, a touch-blow, or he may stop the vibration of the hammer within the plugger altogether for the purpose of manipulating the filling within the tooth. Other varied strokes and arrangements may be had by placing the finger upon an acorn-nut provided upon the plugger-pin, the foregoing objects being attained by the invention fully set forth and described in the following specification and claims, and illustrated in the drawings.

Referring to the drawings, Figure 1 is a 40 complete view showing the device. Fig. 2 is a view of some of the parts in their relation

within the casing. Fig. 3 is a longitudinal sectional view showing all the parts, and Fig. 4 is a sectional view on the line 4-4 of Fig. 3. These views are double the actual size of the instrument and are so made to more plainly show the construction.

Referring to the parts by letters, the casing is divided into three portions—*a*, which is the upper portion, *a'*, which is the intermediate or movable portion for adjusting the tension of the spring on the hammer, and *a''*, which is the swiveled sleeve portion forming a suitable gripping medium for the device and also serving to manipulate the plugger-point and work upon the filling. The upper portion *a* is of substantially the form shown, having the enlarged internally-screw-threaded portion *a³* and the two reduced portions *a⁴* and *a⁵*. Within the reduced portion *a⁴* is an operating-sleeve *B*, which is integral with a shaft *b*, adapted to rotate within the portion *a⁵*. In the screw-threaded portion *a³* of the upper portion is secured the hammer-casing *C*. This casing is substantially uniform throughout its length and has at its upper end a plug *c*, which is provided with slots *c⁵* and a central opening *c²*. The case *C* is further provided with longitudinal slots *c³*. The lower end of the casing is closed by a plug *c⁴*, which is threaded into the same, said plug having a central opening and an external annular groove *c⁶* in an enlarged portion thereof. Located within this hammer-casing *C* is a hammer *D*, which normally rests against the lower plug *c⁴* of the hammer-casing and is retained in this position by the tension of a spring *d*, which surrounds a stem *d'* of the hammer and bears against the enlarged hammer-head, and a collar *d²*, having wings *d³*, which project through longitudinal slots in hammer-casing and are externally threaded for engagement with the threaded casing-section *a'*. This winged collar is loose upon the stem *d'*. This stem *d'* projects up through the opening *c²* in the upper plug *c* and extends into the tubular end *B* of the rotating driving-shaft. This hammer-stem is provided with a cross-pin *d⁶*, which operates in the slots *c⁵*, and with a cam *d⁷*, pinned to the upper end thereof. The cross-pin *d⁶*, operating in the slot *c⁵*, permits the hammer-stem to move up

and down and at the same time prevents the rotation of said stem and the hammer itself. Between this cam d^7 and the plug c and within the sleeve B are interposed two cams d^4 and d^5 , d^4 being a double-faced idle cam, as shown in dotted lines in Fig. 3, and d^5 being a cam opposite in arrangement to the cam d^7 and secured in the lower end of the sleeve B .

On the outside of the hammer-casing C is secured an abutting ring E , which is pinned to said casing and forms an abutment for a coiled spring e , which surrounds the hammer-casing. The intermediate portion a' of the casing also surrounds the hammer-casing, and a shoulder a^6 receives the thrust of the other end of the spring e , thus forcing said intermediate portion a' of the casing upward against the lower end of the upper portion a of the casing. Suitable teeth a^8 are provided between these portions for locking them against relative rotation.

It will be seen from the foregoing description that should it be desirable to change the tension of the spring e upon the hammer the intermediate portion a' of the casing may be pulled down until the teeth a^8 disengage, when said portion of the casing may be rotated and the winged collar d^3 will move endwise, and thus change the tension of the spring as desired. The swiveled sleeve portion a^2 of the casing is secured to the hammer-casing by means of a pin a^{10} , which screws into the said sleeve-casing and projects into the annular groove c^6 of the plug c^4 . Within the lower part of this sleeve portion a^2 of the casing is the plunger-pin F , which is of substantially the form shown in Fig. 2, having a central opening f for the insertion of suitable plunger-points, a shoulder f' to form a bearing for the end of a spring f^2 , which in turn takes against the base of the plug c^4 , the tendency of this spring being to force the plunger-pin outward, and suitable clutch-jaws f^6 , which are forced together by means of an acorn-nut f^3 , screwed thereon. The plunger-pin is further provided with slots f^4 and f^5 . A pin a^9 , screwed into the swiveled portion a^2 of the casing, is arranged to engage either of the slots f^4 f^5 , as desired. The plunger-pin is normally out of engagement with the hammer D .

The operation of the device is as follows: Motion is conveyed to the shaft b in any suitable manner. The rotation of this shaft operates the sleeve B , which is rigidly secured to the cam d^5 . This cam when moving in one direction will engage the floating cam d^4 and rotate the same until the abrupt faces of the cam d^4 and d^7 pass, when the cam d^7 will drop from the highest point of the cam d^4 by the tension of the spring d on the head of the hammer, thus allowing the hammer to descend and convey a stroke to the plunger-pin should the pin be in a position to receive the stroke. If the shaft is rotated in the contrary direction, the cam d^5 will travel to the highest point of the floating cam d^4 , and the cams d^4 and d^5 will drop on passing the ab-

rupt faces and a like impulse be conveyed to the hammer.

The instrument may be used in several different ways. The pin a^9 may be arranged to engage the slot f^4 , as shown, in which case the operator may place his finger upon the acorn-nut f^3 and retain the plunger-pin carrying the plunger-point in an outward position out of range of the hammer for the purpose of manipulating the filling in the tooth or for any other reason. If he should desire to use a stipple-stroke, the plunger-pin is drawn inward by the finger into range with the hammer, when said pin will receive the proper impulses therefrom, or he may apply the plunger-point to the filling, press the instrument forward, and convey a touch-stroke to the filling. It will be noted that during all of these arrangements the hammer has been operating and a certain amount of vibration is conveyed to the entire instrument. On the other hand, the pin a^9 may be arranged to operate in connection with the slot f^5 , in which instance the operator can leave the pin in its outward position out of range with the hammer by placing his finger upon the acorn-nut and using the instrument to manipulate the filling, or he may press in the plunger-pin clear through to the end of the slot, which operation raises the hammer and lifts the cam d^7 out of engagement with the other cams, thus stopping the operation of the hammer. The finger may be gradually moved so as to allow the plunger-pin to return to its normal position by degrees, accordingly as it is desired to obtain a strong or a weak stroke of the hammer upon the pin. The operator may also permit the plunger-pin to assume any relation with respect to the hammer by using his finger, by which a stipple or a touch stroke may be obtained, as desired.

Having described my invention, I claim—

1. In a dental plunger, the combination with the casing consisting of a fixed portion, a relatively rotatable intermediate portion, means for locking the said parts together and a portion swiveled to said fixed portion of a plunger-pin capable of moving longitudinally only therein, a spring holding said plunger-pin normally out of range of the hammer, a reciprocating hammer, a spring acting to move said hammer forward, a rotatable shaft, cams operatively connected with said shaft and hammer and co-operating to draw the hammer back and then release it to the action of its spring, and a regulating device for the hammer-spring in connection with said intermediate portion, substantially as described.

2. In a dental plunger the combination of a casing consisting of a fixed portion carrying a rotatable shaft, an intermediate or movable portion and a portion swiveled to the fixed portion, of a plunger-pin normally held out of range with the hammer, a reciprocating hammer, means for operating and regulating the stroke of the same, and teeth provided between said fixed portion and said interme-

diate portion of said casing, substantially as described.

3. In a dental plugger, the combination of a casing consisting of a fixed portion carrying a rotatable shaft, an intermediate or movable portion, and a portion swiveled to the fixed portion, of a plugger-pin movable longitudinally only in said swiveled portion, a spring whereby said plugger-pin is normally held out of engagement with the hammer, a hammer-casing secured to the fixed portion and having longitudinal slots, a hammer having a stem mounted in said casing to have longitudinal movement therein, a winged collar on said stem and having its wings threaded into said intermediate portion of said casing, teeth provided between said intermediate portion and said fixed portion of said casing whereby they may be locked, and cam connections between said hammer-stem and said shaft whereby motion is conveyed to the hammer, substantially as described.
4. In a dental plugger, the combination of a casing consisting of, first, a fixed portion having teeth on its inner edge; second, a movable intermediate portion having coöperating teeth on its proximate edge and having internal screw-threads, and, third, a swiveled portion, with a hammer-casing secured to the fixed portion and having longitudinal slots, a longitudinally-movable hammer mounted in said hammer-casing, a collar surrounding the hammer-stem and having threaded wings which extend through the slots in the hammer-casing and engage the internal threads of the intermediate portion of the outer casing, a spring thrusting against a shoulder on the hammer and against said collar, a spring acting upon the intermediate portion of the outer casing to hold it in engagement with the fixed part of said outer casing, a reciprocating plugger-pin mounted in the swiveled part of the outer casing, a spring normally holding the same out of range of the hammer, means preventing the rotation of said plugger-pin within the swiveled part of the

casing and limiting its longitudinal movement, a shaft rotatably mounted in the fixed part of the casing, and means intermediate of the shaft and hammer whereby the rotation of the shaft rapidly withdraws the hammer and releases it to the action of its spring, substantially as specified.

5. In a dental plugger, the combination of a casing consisting of, first, a fixed portion; second, an internally-threaded relatively movable intermediate portion adapted to be locked to said fixed portion, and, third, a swiveled portion, with a hammer-casing secured to the fixed portion and having longitudinal slots, a longitudinally-slotted plug closing the upper end of said hammer-casing, a hammer longitudinally movable in said hammer-casing and projecting through said plug, a cross-pin carried by said hammer and movable in the slot in said plug, a tension-collar embracing the hammer-stem and having wings which pass through the slots in the hammer-casing and engage with the internal threads in the intermediate portion of the outer casing, a hammer-operating spring confined between said tension-collar and a shoulder on the hammer, a plugger-pin longitudinally movable in the swiveled part of the outer casing, a spring normally holding it out of range of the hammer, means preventing the rotation of said plugger-pin within said casing and limiting its longitudinal movement, a shaft mounted in the fixed end of the outer casing and having a tubular inner end, a cam secured to said tubular end of the shaft and through which the hammer-stem passes, a double-faced cam loosely mounted in the shaft end and embracing the hammer-stem, and a cam projection fast on the hammer-stem with which the last-named cam may engage.

In testimony whereof I hereunto affix my signature in the presence of two witnesses.

ALDEN BUSH.
